UPRIGHT STEAM BOILER

Charles K. Matthews, Wichita Falls, Tex.

Application March 11, 1935, Serial No. 10,515

1 Claim. (Cl. 122—125)

It is well known that upright steam boilers having flues require frequent replacement of the flues because of the rapid erosive action thereon at the water line. This is objectionable 5 chiefly because of the expense of maintenance and the loss incident to the shutting down of the boiler when making repairs.

Therefore, an essential feature of the invention is the provision of an upright boiler of the flue 10 and tubular type having the flues completely submerged in water so as not to present a water line for erosive action.

The invention furthermore aims to devise a steam boiler of the nature aforesaid which presents a maximum heating surface and embodies 15 a lower main portion and an upper removable auxiliary portion whereby access to the interior may be readily had for any desired purpose.

A further intent of the invention is the construction of a boiler of the type stated in which 20 impurities in the water are separated both by precipitation and flotation and collect at the bottom of the boiler as sediment and at the top of the boiler as scum to be blown or drawn off 25 at intervals, as desired.

While the drawings illustrate a preferred embodiment of the invention, it is to be understood that in adapting the means to meet specific needs and requirements the design may be varied and 30 changes in the minor details of construction may be resorted to within the scope of the invention as claimed without departing from the spirit thereof.

For a full understanding of the invention and 35 the merits thereof, reference is to be had to the following description and the drawings hereto attached, in which:

Figure 1 is a vertical central sectional view of 40 an upright steam boiler of the flue and tubular type illustrative of an embodiment of the invention, taken on the line 1—1 of Figure 2, and looking in the direction indicated by the arrows.

Figure 2 is a plan section on the line 2—2 of Figure 1.

Figure 3 is a horizontal section on the line 3—3 of Figure 1.

Figure 4 is a view similar to Figures 2 and 3 on the line 4—4 of Figure 1.

Corresponding and like parts are referred to 50 in the following description and designated in the several views of the drawings by like reference characters.

The body of the boiler comprises a lower main portion 5 and an upper removable portion 20 to 55 admit of access to the interior for any desired

purpose. Flue sheets 5a and 5b are disposed within the shell 5 and support flues 10. A fire box 11 is disposed below the flue sheet 5b and has a door opening 12 in a side thereof. A perforate pipe 14a adjacent the flue sheet or bottom 5b projects beyond the side of the boiler and connects with a pipe 14 for carrying off the sediment. A water inlet pipe 13 connects with the lower port of the boiler.

A drum or auxiliary boiler 6, is located within 10 the upper removable portion or shell 20, and is spaced therefrom and from the main boiler. A pipe 7 connects the lower portion of the auxiliary boiler 6 with the upper portion of the main boiler 5. A branch 7b extends through the 15 shell 20 and connects with the auxiliary boiler 6 a short distance above its bottom to maintain a supply of water therein and prevent burning of the bottom. A branch 7a extends within the boiler 5 and terminates adjacent the flue sheet or top 5a, to prevent the formation of 20 a space and consequent water line in the upper portion of the main boiler 6. These branches 7a and 7b form parts of the connecting pipe 7. A pipe 8 connects the lower portion of the auxiliary 25 boiler 6 with the lower portion of the main boiler 5. A branch 8b extends through the shell 20 and connects with the auxiliary boiler a short 30 distance above the bottom thereof. A branch 8a extends within the main boiler and terminates some distance from the bottom thereof. A pipe 9, corresponding to the pipe 8, similarly connects the main and auxiliary boilers.

The boiler is equipped with the usual steam gauge 24, water gauge 25, and safety valve 26. 35 The steam pipe 19 leads from the upper part of the auxiliary boiler through the shell 20. A pipe 17, similar to and for a like purpose as the pipe 14, has a perforate extension 17a within and adjacent the bottom of the auxiliary boiler 40 6 for carrying off sediment.

A scum trap 22 within the upper portion of the auxiliary boiler 6 is of conical formation and has a pipe 18 leading from its apex through the sides of the shells 6 and 20 to carry off the 45 impurities collecting in the trap. The pipes 18, 17 and 14 contain valves to admit of discharging the impurities at desired intervals. The trap 22 is supported within the boiler by stay bolts 23, or in any preferred manner, and operates as a 50 baffle to prevent water passing off through the several pipe connections leading from the upper part of the boiler 6.

It will be understood from the foregoing and by reference to the accompanying drawings that 55

an upright steam boiler constructed in accordance with the invention is free from any water line and the fire tubes are completely submerged, hence there is no opportunity for the erosive 5 action so destructive to the flues of upright boilers as generally constructed. It is further noted that the system of connecting pipes 7, 8 and 9, insures a positive circulation of water and rapid heating thereof. The disposition of the auxiliary boiler 6 results in a large area of heating 10 surface. By having the pipes 7, 8 and 9 connect with the boiler 6 some distance above the bottom thereof, provision is had for trapping water in the lower portion of the auxiliary boiler to 15 prevent burning of the bottom thereof. The top of the boiler is closed by a bonnet 21 to which a pipe may be fitted for carrying off smoke or hot gases.

Having thus described the invention, what is claimed as new is:

In combination, a vertical fire tube boiler, a casing arranged to seat upon the top of said boiler and defining a flue space, a steam and 5 water drum arranged in said casing above said boiler and spaced from the walls thereof, said steam and water drum having connections extending exteriorly of said casing and connecting the top of said boiler and the bottom of said 10 boiler respectively with said drum so as to provide for circulation therebetween, and a conical surface blow off scum trap located adjacent the normal water level of said drum, said scum trap having connection at the bottom to a blow off 15 pipe extending to the exterior of said casing.

CHARLES K. MATTHEWS.
